UNITED STATES PATENT OFFICE

EDWARD T. BENTON, JR., OF WASHINGTON, DISTRICT OF COLUMBIA, ASSIGNOR TO THE AMERICAN DETACHABLE SHOE HEEL COMPANY, INCORPORATED, A CORPORATION OF VIRGINIA.

DETACHABLE HEEL.

995,656.

Specification of Letters Patent. Patented June 20, 1911.

Application filed February 24, 1910. Serial No. 545,628.

To all whom it may concern:

Be it known that I, EDWARD T. BENTON, Jr., a citizen of the United States, residing at Washington, in the District of Columbia, 5 have invented new and useful Improvements in Detachable Heels, of which the following is a specification.

This invention relates to certain new and useful improvements in detachable heels for 10 boots and shoes.

The invention has for its object the provision of simple and inexpensive means whereby the worn outer lifts of a boot or shoe heel may be readily and quickly re- 15 placed or renewed by new and perfect lifts.

A further object is to provide an improved fastening device for a detachable heel which is completely concealed from view when in use, which will insure a water tight joint, 20 and which is not exposed to wear or deterioration incident to the use of the boot or shoe to which it is attached.

The invention will be hereinafter fully set forth and particularly pointed out in the 25 claims.

In the accompanying drawing:—Figure 1 is a longitudinal sectional view of my improved heel, including a portion of a shoe. Fig. 2 is a bottom plan view with the de- 30 tachable lift portion removed. Fig. 3 is a top view of the detachable portion. Figs. 4 and 5 are details illustrating the clamping plates. Figs. 6 and 7 are views of slightly modified forms of bearing plate and clamp- 35 ing plate respectively. Fig. 8 is a sectional view illustrating another form of bearing plate. Fig. 9 is a detail view of a locking device for the clamping screw. Fig. 10 is a sectional view of the heel with the clamping 40 plate reversed.

Referring to the drawing, 10 designates the outer sole of a shoe, 11 the inner sole, and 12 the permanently attached heel portion. The outersole 10 is provided with a 45 recess or depression to receive a countersunk plate 13 provided with a central opening coinciding with a sleeve 14 extending transversely through the lifts forming the heel portion 12. The bottom lift of said 50 heel portion is provided with a recess or chamber to receive a plate 15 which may be secured in position by means of glue 16 as indicated in Fig. 1, or screws 17 as indicated in Fig. 2. Said plate is provided with a

central opening 19 coinciding with sleeve 14, 55 and a plurality of lugs or pins 20.

The detachable portion 21 is formed of any desirable number of lifts united in the usual way, the number preferably employed being that usually affected in the wear of 60 the shoe. The inner lift of the detachable portion is provided with a recess 22 to receive a plate 23 provided with a central threaded boss 24 adapted to receive the threaded end of a clamping screw 25, the 65 head 26 of which is located in the countersunk plate 13 beneath the inner sole 11. It will be noted that the walls of recess 22 extend slightly above the plate 23, whereby the said plate 23 and plate 15 are separated 70 by a space when the detachable portion is placed in position and insuring a perfect clamping action. The plate 23 is secured in position by any suitable means, such as screws 27. Said plate 23 is provided with 75 recesses 29 to receive the pins or lugs 20 whereby the detachable portion 21 is held from rotating relatively to the permanent heel portion 12.

The plates 15 and 23 may be of any suitable shape, various forms being illustrated in the drawings. It is also obvious that where it is desired to reduce the number of lifts forming the detachable portion 21 the plate 23 may be reversed so that boss 24 will 85 project into the opening 19, as illustrated in Fig. 10.

In order to prevent accidental rotation of the screw 25 I provide a locking device 35 provided with spurs 36 adapted to be forced 90 into the under sole, a lug 37 being provided to engage the slot in the screw.

In Fig. 8 I have shown a modification in which plate 15^a is held in place by means of spurs 18 struck up therefrom, in lieu of the 95 screws 27 of Figs. 1, 2 and 3. In Figs. 6 and 7 the plates 15' and 23', respectively are identical with plates 15 and 23 except as to contour.

In practice, when the lifts of the detachable portion 21 become worn it is only necessary to lift the lining of the shoe and turn screw 25 by means of a small screw driver, until the plate 23 is disengaged therefrom whereupon a new detachable portion may be 100 readily and quickly substituted therefor. It will be observed in this connection that the space between the plates 15 and 23 per-

mits the center of the detachable portion to move slightly farther than the edge thereof, thereby insuring a perfect clamping action and an absolutely water tight joint. It is 5 also obvious that by means of my invention worn out heels may be readily replaced by persons having no knowledge or skill in connection with the art of shoe making.

One of the important points of utility of 10 my improved detachable heel is that the dealer can furnish an extra set of detachable heel portions with each pair of shoes, thereby practically furnishing the customer with two heels for each pair of shoes.

15 Having thus explained the nature of my invention and described a manner of constructing and using the same, although without attempting to set forth all of the forms in which it may be made or all of the modes 20 of its use, what I claim is:—

1. The combination with a shoe having a heel portion permanently attached thereto, a bearing plate carried thereby and having its outer face in the same plane as the outer face 25 of said heel portion, said plate being provided with a central opening, and a clamping screw extended through said heel portion, of a detachable heel portion comprising a plurality of lifts and having a recess in 30 its upper face, and a clamping plate located in said recess provided with a normally depending central boss for engaging said

screw, said clamping plate being reversible to accommodate itself to a detachable portion of fewer lifts, said boss fitting through 35 the central opening in the bearing plate when the clamping plate is reversed.

2. The combination with a shoe having a heel portion permanently attached thereto, a bearing plate attached to the outer face 40 thereof and provided with depending pins and a central opening, and a clamping screw extended through said heel portion, of a detachable heel portion comprising a plurality 45 of lifts, and a clamping plate secured to said detachable portion and provided with a central threaded boss to engage said screw, said clamping plate being reversible to accommodate itself to a detachable portion constructed of fewer lifts, said boss fitting through 50 the central opening in said bearing plate when the clamping plate is reversed, said clamping plate being provided with openings 55 to receive the lugs of said bearing plate in either position of said clamping plate.

In testimony whereof I have hereunto set my hand in presence of two subscribing witnesses.

EDWARD T. BENTON, Jr.
